(57) **CLAIM**

I claim the ornamental design for a decorative electrical switch, as shown and described.

DESCRIPTION

FIG. 1 shows a front view of the decorative electrical switch showing the new design;

FIG. 2 shows a top view thereof;

FIG. 3 is side view thereof; and,

FIG. 4 perspective view thereof.

In FIGS. 1-4, the broken line illustration of the environmental structure forms no part of the claimed invention.

1 Claim, 1 Drawing Sheet

FIG. 2

FIG. 1

FIG. 3

FIG. 4
